UNITED STATES PATENT OFFICE.

EDWARD HERMAN KLEINFELDT, OF NEW YORK, N. Y.

WALL CONSTRUCTION.

1,362,327.

Specification of Letters Patent. Patented Dec. 14, 1920.

Application filed July 26, 1919. Serial No. 313,482.

To all whom it may concern:

Be it known that I, EDWARD HERMAN KLEINFELDT, a citizen of the United States, and a resident of Bronx, in the county of New York and State of New York, have invented certain new and useful Improvements in Wall Constructions, of which the following is a specification.

My invention relates in general to an improved wall construction and more particularly to the improved building blocks which constitute the elements from which the wall is constructed.

An important object of my invention is to provide an improved building block especially adapted for use in double wall constructions and which is so constructed and arranged that the inner and outer walls of the double wall will be bound together by a positive and continuous structure of homogeneous bond.

Another important object is to provide an improved building block of such construction that it may be correctly, easily and quickly laid to form a strong and durable wall of neat and attractive appearance, without requiring the exercise of skill and dexterity on the part of the mason, thereby presenting labor saving features; and which is also adapted to reduce to a minimum, or entirely eliminate, any waste of the binding material.

Other objects and advantages reside in the certain novel features of the construction, arrangement and combination of parts, and will become apparent as the description proceeds, reference being had to the accompanying drawing forming part of this specification, and in which:—

40 Figure 1 is a perspective view of a portion of a single wall,

Fig. 2 is a vertical cross section on line 2—2 of Fig. 1,

Fig. 3 is a perspective view showing the angle blocks and their relation to the wall, the wall being shown in dotted lines,

Fig. 4 is a detail perspective view of an angle block,

Fig. 5 is a detail perspective view of a block adapted for use in double wall constructions,

Fig. 6 is a vertical cross section of the double wall.

Referring to the drawing, particularly to Fig. 6, it will be seen my invention preferably comprises an outer wall 10 and an

inner wall 11. Both the inner and outer walls consist of any desired number of horizontal courses of the building blocks to be hereinafter more fully described.

The building blocks embodying my invention are provided with a longitudinal channel 12 in their upper face and a longitudinal flange 13 on their lower face. The channel 12 is adapted to be filled with bonding material such as cement, mortar, or the like. The flange 13 of the blocks of one course are adapted to be fitted in the channels 12 of the lower course and the size of the flange is so proportioned to the size of the channel that when the flange is placed in the channel after the channel has been filled with bonding material, it displaces so much of the bonding material as will be necessary to spread between the adjacent faces of the blocks and bind the same together.

The angle blocks, as shown in Figs. 3 and 4, consist of a long arm 14 and a short arm 15 integral therewith. The channel and flange of this block are identical with the channel and flange of the ordinary block and need not be further described. As seen in Fig. 3, the arrangement of the angle blocks in one course is reversed in the adjacent course so that the long arm of the angle block of one course is disposed above the short arm of the angle block of the adjacent course to attain the proper break joint relation of the courses.

In the double wall construction, the blocks constituting the inner or the outer wall, as desired, and shown for the sake of illustration as constituting the outer wall, are provided with a longitudinal rib 16 along the lower edge of its inner side. This rib serves to properly space the walls from each other and also serves to support the bonding material which binds the two walls together until the same has set, as will be hereinafter more fully described.

The blocks of both the inner and outer walls are provided with openings 17 which extend from the bottom of the channel through the block structure and terminate in the inner face thereof. When the blocks are laid in place, the flange on the lower face thereof, besides forcing the bonding material between the faces of each of the blocks, forces a portion of it downwardly through the openings into the space between the walls. It is to be noted that this occurs in

both the inner and outer walls and this bonding material rests upon the rib 16 until set. If desired, additional bonding material may be placed in the space, but ordinarily that which is forced through the openings is sufficient to provide a continuous, homogeneous and positive structure of bonding material between the courses constituting each of the walls, and between the walls themselves.

10 If desired, the top course may comprise a block having a flat top surface with the usual flange on its lower surface, as shown in Fig. 3.

In practice, the walls may be easily, 15 quickly and correctly laid as the angle blocks provide for the proper break joint relation of the courses of the walls. The interfitting flange and channel provide not only for the proper alinement but also serve as a measure 20 for the amount of bonding material to be used and the large amount of bonding material which usually is extruded from between the surfaces of the blocks, and which is usually scraped off and thrown away by 25 the mason, is reduced to a minimum, or entirely eliminated, and the inner and outer walls of the double wall are properly spaced and bound together.

As seen in Fig. 6, the bonding material 30 extends from the channel of the blocks of each wall between the horizontal courses and downwardly through the openings or into the space between the walls and may with the proper addition of a sufficient 35 bonding material entirely fill the space as shown in the lower course, or may only partly fill the space, as shown in the second and third courses.

I claim:

0 1. An improved wall construction comprising inner and outer walls consisting of a plurality of courses of building blocks having a channel in their top face adapted to be filled with bonding material and a 45 flange on their opposite face proportioned in cross sectional area with respect to the cross sectional area of said channels, all of said blocks being provided with a plurality of openings extending from the bottom of the channels through the block structure to the inner face thereof and adapted to receive bonding material from the channels, and a spacing rib on each of said blocks of one of said walls adapted to properly space said 50 inner and outer walls and to receive and support the bonding material received from the openings of said blocks, as and for the purposes set forth.

2. An improved wall construction com-

prising inner and outer walls consisting of a plurality of courses of building blocks having a channel in their top face adapted to be filled with bonding material and a flange on their opposite face proportioned in cross sectional area with respect to the cross sectional area of said channels, all of said blocks being provided with a plurality of openings extending from the bottom of the channels through the block structure to the inner face thereof, whereby when 75 the flange of the blocks of one course is inserted in the channel of the blocks of the other the bonding material is displaced through the openings and spread between the faces of the blocks.

3. An improved wall construction consisting of a plurality of courses of building blocks having a channel in their top face adapted to be filled with bonding material, and a flange on their opposite face proportioned with respect to said channel, said blocks being provided with a plurality of openings extending from the bottom of the channels through the block structure to the inner face thereof, substantially as and for 80 the purposes set forth.

4. An improved wall construction comprising inner and outer walls, the elements 85 of each of said walls having an opening extending from the horizontal face to the interior vertical face thereof, spacing means between said walls and a homogeneous bond of positive and continuous structure extending through said openings and between said walls thereby entirely surrounding positive 90 portions of each of said walls to bind said walls together, all as and for the purposes set forth.

5. An improved wall construction comprising inner and outer walls, the elements 100 of each of said walls having an opening extending from the horizontal face to the interior vertical face thereof, and a homogeneous bond of positive and continuous structure extending through said openings 105 and between said walls thereby entirely surrounding positive portions of each of said walls to bind said walls together, all as and for the purposes set forth.

6. An improved building block having a 110 channel in its top face and openings extending from the bottom of said channel through the positive block structure to the inner face thereof to permit the passage of bonding material therethrough, all as and for the 115 purposes set forth.

EDWARD HERMAN KLEMPFELDT.
